United States Patent Office.

FREDERICK E. HOTCHKISS, OF GLOVERSVILLE, NEW YORK.

Design No. 4,859, dated May 2, 1871.

DESIGN FOR PALM AND BACK PIECES OF GLOVES.

The Schedule referred to in these Letters Patent and making part of the same.

To all whom it may concern:

Be it known that I, FREDERICK E. HOTCHKISS, of Gloversville, in the county of Fulton and State of New York, have invented a new and original Design for Palm and Back Pieces of Gloves; and I do hereby declare that the following is a full, clear, and exact description thereof, which will enable others skilled in the art to make and use the same, reference being had to the accompanying drawing forming part of this specification, in which—

Figure 1 is a diagram, showing the palm and back pieces joined together.

Figure 2 is a diagram, showing two palm pieces and the advantageous method of cutting the same.

Figure 3 is a diagram, showing two backs and the advantageous methods of cutting the same.

Similar letters of reference indicate corresponding parts.

This invention relates to a new design for the palms and backs of gloves, and has for its object by such new design to provide an advantageous manner of cutting the material to economize the same.

The invention consists, first, in so shaping the palm that back and face of forefinger are left on it, while at the wrist the division will be in line with the middle of the thumb.

Secondly, the invention consists in so shaping the back of the glove that it will be without the forefinger, while at the wrist it extends to the middle of the thumb.

A in the drawing represents a palm piece of my design.

It embraces the palms *a*, *b*, and *c* of the second,

third, and fourth fingers, and also the palm *d* and back *e* of the forefinger.

From the back of the forefinger it is cut slanting, as at *f*, toward the thumb-opening *g*, whence a straight line, *h*, extends to the wrist, so that at the wrist the back and palm will be separated by a seam which is in line with the division between the parts *d e* of the forefinger and with the middle of the opening *g*.

By this mode of cutting I am enabled to cut palms to advantage, as is clearly shown in fig. 2, where two such palm pieces, *A*, are shown placed together as they are cut from one piece.

B is the back of the glove.

It has the backs *i*, *j*, and *k* of the second, third, and fourth fingers, but is wider at the wrist to extend to *m*, which is the middle of the thumb-opening, as shown. It is, therefore, cut slanting, as at *l*, from the second finger to said opening.

By this arrangement the glove backs can also be advantageously cut, as shown in fig. 3.

When the palm *A* and back *B* are put together, as in fig. 1, they will touch at the lines *l f* and *m h*.

The parts of the glove thus shaped can be made of leather, cloth, or other suitable fabric, both being of different material or of the same, as may be desired.

I claim as my invention—

1. The design for the palm *A* of a glove, as shown.
2. The design for a back, *B*, of a glove, as shown.

FREDERICK E. HOTCHKISS.
